UNITED STATES PATENT OFFICE.

AUGUST W. BLEYLE, OF BERKELEY, AND JOHN J. DAVIS, OF OAKLAND, CALIFORNIA,
ASSIGNORS TO H. WARD DAWSON, OF SAN FRANCISCO, CALIFORNIA.

ELEVATOR SAFETY DEVICE.

1,411,770.

Specification of Letters Patent.

Patented Apr. 4, 1922.

Application filed May 12, 1921. Serial No. 468,904.

To all whom it may concern:

Be it known that we, AUGUST W. BLEYLE and JOHN J. DAVIS, citizens of the United States, residing at Berkeley and Oakland, respectively, in the county of Alameda and State of California, have invented certain new and useful Improvements in Elevator Safety Devices, of which the following is a specification.

10 This invention relates to an elevator safety device, and more particularly to a simple construction adapted for manufacture and installation at little cost, and by the use of which an elevator is prevented from 15 being operated until such time as the elevator doors are in closed position.

By the present invention, the elevator operator is unable to complete the elevator operating circuit until such time as the door 20 latch is in locked position assuring the closing of the door, and precluding the opening thereof.

An object of the invention is to provide, among other things, a particular form of 25 switch lever which is positively operated to a position to break the elevator controlling circuit by the releasing movement of the door controlling latch bolt thereby precluding the accidental maintaining of the circuit at such time as the elevator door is 30 opened.

A further object is to provide a construction wherein the latch bolt and switch lever are so constructed as to contain little metal 35 and to be of very light weight, and which when in co-operative relation will have a positive interlock which insures the manual operation of the switch lever by the pivotal movement of the latch bolt in either direction.

40 A further object is to incorporate a spring contact in connection with the switch lever for completing the elevator control circuit whereby a positive contact between the stationary contact members within the elevator 45 circuit line will be maintained.

With the above mentioned and other objects in view, the invention consists in the novel construction and combination of parts 50 hereinafter described, illustrated in the accompanying drawings, and set forth in the claims hereto appended, it being understood that various changes in the form, proportion, size and minor details of construction 55 within the scope of the claims may be re-

sorted to without departing from the spirit or sacrificing any of the advantages of the invention.

To more fully comprehend the invention, reference is directed to the accompanying 60 drawings, wherein:—

Figure 1 is a view in elevation of the preferred embodiment of our invention illustrated with the elevator door in open position.

65 Figure 2 is a view in end elevation taken on line 2—2 of Figure 1.

Figure 3 is a view similar to Figure 1 with the elevator door in closed position.

Figure 4 is a sectional view taken on line 70 4—4 Figure 3, viewed in the direction of the arrow.

Figure 5 is a vertical sectional view taken on line 5—5 of Figure 3 illustrating the vertical slot within the switch lever, and the 75 latch guiding tongue.

Figure 6 is a view in front elevation of the lock casing.

Figure 7 is a sectional view on line 7—7 of Figure 3 disclosing the stationary contacts.

Figure 8 is a view in perspective of the switch lever, and

Figure 9 is an inverted perspective view of the latch bolt illustrating the guiding tongue.

85 Referring more particularly to the several views of the drawings wherein like characters of reference designate corresponding parts, 1 is a door casing, and 2 is a door frame carrying one or more supporting 90 wheels 3 which operate on the supporting door rail 4. The door frame is moved longitudinally of the rail 4 in any suitable manner to and from the casing 1. Secured to the casing 1 is a suitable lock case 5, the 95 outer face of which is open and is adapted to be closed by a removable cover plate 6 detachably secured thereto by screws or other means 7. The casing front wall facing the door frame is at its lower end formed 100 with a latch bolt receiving opening 8, and the upper wall surface of said opening is inwardly turned forming a latch bolt head engaging part 9, Figures 1 and 2 of the drawings.

Secured to the inner face of the upper 105 wall surface of the case 5 is a piece of suitable insulating material 10 carrying on its under face the spaced stationary contacts 11 from which lead the wires 12 forming the elevator operating circuit. The contacts 110

11 are adapted to be connected by a suitable movable contact 13 in the form of a disk carried by a supporting post 14 extending upwardly from an insulating base 15 carried 5 on the upper wall surface of a switch lever 16. A spring 17 coiled about the post 14 normally forces the contact 13 against the head of the post, and enables the same to be yieldably mounted on said post and normally 10 maintained in tight contact with the stationary contacts when the switch lever is moved to closed position. The lever 16 is at its rear end mounted to swing on a horizontal fulcrum 18 adjacent the rear wall of 15 the lock case 1, and the enlarged forward end of said lever is adapted to fall by gravity in rear of the case opening 8 and adjacent said opening is transversely slotted as at 19 forming the upper and lower furcations 20 and 21, between which is adapted to be received 20 the enlarged head of a suitable latch bolt hereinafter described. The lower furcation is vertically slotted inwardly from its free end, as at 22, affording parallel fingers 23 25 providing a guide for the hereinafter described latch bolt. The extreme forward end of the upper edge of the lever 16 is provided with a stop 24 for resting on the upper surface of the part 9 when the free end of the 30 lever 16 is in open position, as in Figure 1.

Pivotaly mounted within its length at the forward end of the door frame 2 to swing on a horizontal fulcrum 24 is a latch bolt 25, the rear end of which is pivotally 35 connected as at 26 to a vertically movable bolt operating rod or member 27. The rod 27 is adapted to be raised in the direction of the arrow, Figure 3, in any suitable manner, either by the vehicle operator, or automatically 40 when it is desired to release the latch bolt 25, and the weight of the member 27 normally maintains the free forward end of the latch bolt 25 in its raised position, as in Figures 1 and 2 of the drawings. The forward end of the latch bolt 25, which extends beyond the door frame 2, is adapted to be projected through the casing opening 8 on the closing of the door, as illustrated in 45 Figure 3, and said free end is provided with the upwardly extending latch head 28 formed with a locking face 29 adapted to engage in rear of the substantially vertical face or surface 30 of the part 9. On its under surface, the free end of the latch bolt 50 25 is cut away inwardly on opposite sides from its outer end, as at 31, forming a longitudinal guiding tongue 32 adapted for reception within the vertical slot 22 in the lower furcation 21 of the lever 16. The distance between the upper surface of the portions 21 and the top of the latch head 28 is approximately equal to the distance between adjacent surfaces of the furcations 20 and 21, whereby the latch head when projected 55 through the opening 8 will be received in

the transverse slot 19 and will occupy approximately all of the space afforded thereby, whereby the weight of the latch operating member, in causing the free end of the latch bolt to move upwardly, will cause a 70 positive operation of the lever 16. Under normal conditions, the downward movement of the latch head 28 by upward movement of the member 27 releases the pressure against the furcation 20, and permits the same to 75 drop by gravity breaking the contact between the members 13 and 11, but should said contacts for any reason freeze and preclude the dropping by gravity of the lever 16, the positive movement of the head 28 80 downwardly to enable the surface 29 thereof to clear the face 30 of the opening 8, would cause the under cut portions 31 of the latch to contact with the fingers 23 and positively force the free end of the switch lever 16 85 downwardly to break the elevator operating circuit prior to such time as it would be possible to open the elevator door. By forming the guiding tongue 32 on the under surface of the free end of the latch bolt 25, and by 90 providing the slot 22 in the lower furcation 21 of the lever 16, the guiding of the latch bolt in its proper position transversely of the lever is at all times assured and the operative movement of the free end of latch 95 bolt is reduced to a minimum to obtain the required movement of the lever 16.

Having thus described our invention what we claim as new and desire to secure by Letters Patent of the United States is:— 100

1. A safety lock for elevator shaft doors comprising a lock case fixed to the door casing and provided with a latch bolt receiving opening in one wall thereof, a horizontally fulcrumed headed latch bolt carried by 105 the door to move longitudinally therewith to be projected through the case opening and interlock with the wall thereof, a switch lever pivotally mounted at its rear end within the lock case and with its forward end facing said case opening and adapted to drop by gravity to a point in rear of said opening, the forward end of said lever having a transverse slot affording upper and lower parallel furcations between which 115 said headed latch bolt is adapted to snugly fit on the insertion of the same within the latch bolt receiving opening whereby said lever is positively operated on its fulcrum by the swinging movement of said latch bolt, 120 a stop on the lever, a part on the lock case with which said stop contacts to limit the downward swinging movement of the lever, a pair of stationary contacts, a contact carried by the lever and adapted to complete 125 the circuit between said stationary contacts, and means for normally forcing the headed end of the latch upwardly and to overbalance the weight of the lever whereby on the reception of said latch head within said case 130

opening, said lever is automatically and positively operated to make said contacts, and whereby on the lowering of said latch said lever is positively operated to break 5 said contacts should the switch lever fail to drop by gravity.

2. A safety lock for elevator shaft doors comprising a lock case fixed to the door casting and provided with a latch bolt receiving 10 opening in one wall thereof, a horizontally fulcrumed headed latch bolt carried by the door to move longitudinally therewith to be projected through the case opening and interlock with the wall thereof, said latch being cut away at opposite sides of its under 15 face affording parallel shoulders forming a longitudinal guiding tongue between them, a switch lever pivotally mounted at its rear end within the lock case and with its forward end facing said case opening and adapted to drop by gravity to a point in rear 20 of said opening, the forward end of said lever having a transverse slot affording upper and lower parallel furcations between 25 which said headed latch bolt is adapted to snugly fit on the insertion of the same within the latch bolt receiving opening whereby

said lever is positively operated on its fulcrum, by the swinging movement of said latch bolt, the lower furcation being vertically slotted inwardly from its free end affording parallel fingers between which 30 said latch guiding tongue is received and on which said shoulders bear, a stop on the lever, a part on the lock case with which 35 said stop contacts to limit the downward swinging movement of the lever, a pair of stationary contacts, a contact carried by the lever and adapted to complete the circuit between said stationary contacts, and means 40 for normally forcing the headed end of the latch upwardly and to overbalance the weight of the lever whereby on the reception of said latch head within said case opening, said lever is automatically and positively 45 operated to make said contacts, and whereby on the lowering of said latch said lever is positively operated to break said contacts should the switch lever fail to drop by gravity. 50

In testimony whereof we have signed our names to this specification.

AUGUST W. BLEYLE.
JOHN J. DAVIS.
